UNITED STATES PATENT OFFICE.

JAMES H. ROBERTSON, OF BROOKLYN, NEW YORK.

ELECTRIC TELEPHONE.

SPECIFICATION forming part of Letters Patent No. 276,631, dated May 1, 1883.

Application filed August 17, 1882. (No model.)

To all whom it may concern:

Be it known that I, JAMES H. ROBERTSON, of the city of Brooklyn, in the county of Kings and State of New York, have invented a new 5 and useful Improvement in Electric Telephones, of which the following is a specification, reference being had to the accompanying drawings, forming part of the same.

Figure 1 is a face view of an apparatus containing my improvement, and Fig. 2 is an edge view of the same.

My invention relates to the supporting and retaining in its place in a telephone of the vibrative diaphragm, so as to secure the utmost 15 possible freedom of vibration; and it consists of the devices hereinafter described and claimed.

The drawings show my invention as applied to a telephone-transmitter. It may also be applied to the diaphragm of a receiver.

A is the diaphragm. It is represented as secured to a door, B, of a case intended to inclose the apparatus. The mouth-piece (not shown) communicates with the diaphragm 25 through an aperture (also not shown) in the door.

a is one of the electrodes, fixed to the center of the diaphragm, and b is the other electrode, suspended from the bracket C by the wires c 30 c', as shown in Fig. 1.

d d' are the circuit-wires, the former connected to the bracket C and the latter to the diaphragm A, thus establishing the circuit over the said wires and through the bracket 35 C, the wires e e', the diaphragm A, and the electrodes a and b. The wire d' may connect directly with the electrode a.

The method described and shown of suspending the electrode b, I regard as new; but 40 I do not intend to claim it in this specification. I reserve it for a separate patent for which I purpose making application. Nor do I here

limit myself to the particular device described for arranging and holding the electrode b in contact with the electrode a. Any other known 45 device for the purpose may be employed.

My improvement relates, as before stated, to the devices employed for supporting and retaining in place in the telephone the diaphragm. The method heretofore employed 50 has been to support the diaphragm by its rim on a rigid or a yielding or elastic substance, and in some suitable way secure it on such support. With this arrangement the entire perimeter of the diaphragm is supported by 55 and in contact with the supporting substance, which necessarily suppresses or interferes somewhat with the vibrations of the diaphragm in response to the impulses from the sound-waves. I have found that by supporting the 60 diaphragm, near its perimeter, at several separate points, its vibratory action is improved. The circles a' a² a³ in dotted lines in Fig. 1 show where I place the supports, and at a' a², Fig. 2, are shown two of the supports. These 65 are made of rubber in the form of small disks or short studs attached by cement preferably to the door B. Preferably three of these supports are used, as that is the smallest number that will properly support the diaphragm. 70 They may be placed about equidistant from each other just within the perimeter of the diaphragm, which is attached to them by any suitable means, preferably cement.

What I claim as my invention, and desire 75 to secure by Letters Patent, is—

The diaphragm A, supported and secured in its place in a telephone at separate points only by means of the rubber disks or studs a' a² a³, as and for the purpose described.

JAMES H. ROBERTSON.

In presence of—

P. B. VERMILYA,
A. G. N. VERMILYA.
